UNITED STATES PATENT OFFICE.

WILLIAM H. APPLEMAN, OF BELMONT, NEW YORK.

AUTOMOBILE JACK.

Application filed December 19, 1919. Serial No. 346,180.

To all whom it may concern:

Be it known that I, WILLIAM H. APPLEMAN, a citizen of the United States, and a resident of Belmont, in the county of Allegany and State of New York, have invented a new and useful Improvement in Automobile Jacks, of which the following is a specification.

My invention relates especially to the means for raising and supporting the axle of the vehicle in any desired position without relying upon the usual forms of latching devices now in use for a like purpose.

The object of my invention is to provide a plunger actuating device for jacks, steering gears, and similar devices which is not only more durable but also easier and far more convenient and reliable as well as easier of application and operation than devices now in use for a like purpose.

I attain the foregoing objects in the mechanism illustrated in the accompanying drawings, in which,—

Fig. 1 is a right hand side elevation view, partly in section with portions removed in order to reveal the relation of interior parts.

Fig. 2 is a rear elevation view, chiefly in transverse section, said section line being distorted but running near enough a central line to reveal the relative positions of all internal as well as external members.

Fig. 3 is a left side elevation view of my device assembled ready for use, less the operating handle but including the ratchet lever.

Fig. 4 is an edgewise view of the naked stub portion of the ratchet lever shown in Figure 3 and in which its blade portion and handle socket are more clearly disclosed.

Fig. 5 is a horizontal plan view of a plain type handle adapted to use with the ratchet lever illustrated in Figures 1, 2 and 3 in case of an emergency.

Fig. 6 is a plan view of a modification of the ratchet lever as illustrated in Figure 3 in connection with a suitable telescopic handle adapted to be used with it, as well as with the levers shown in Figures 3, 6 and 8.

Fig. 7 is a plan view of the internal member of the telescopic handle disclosed in Figure 6.

Fig. 8 is a plan view, partly in section

of the lever and telescopic handle disclosed in Figure 6 taken from its opposite side and with the dog and latching devices omitted.

Fig. 9 is a right hand side view of a modification of my device.

Fig. 10 is a rear view of said modification partly in section, taken on a distorted line but near enough a vertical center to reveal the relation of all internal as well as external members.

Fig. 11 is a left hand side elevation of said modification, partly in section with portions removed in order to more clearly reveal the construction and relation of the various members.

Fig. 12 is a transverse view in section of member 22^a of Figure 11.

The lever and handle shown in Figures 6 and 7 are interchangeable with the lever and handle throughout the several different figures.

In Figures 1 to 3 inclusive, a suitable housing or casing 1 is provided for enclosing and maintaining alignment of the working members. It consists of a relatively small tubular chamber supported in a vertical position by a foot or pedestal and having intermediate of its ends a relatively large transverse chamber, preferably circular in form, a portion at least of the circular walls of said transverse chamber being machined or otherwise made suitable to serve as a circular journal bearing. Preferably one of the side walls of said housing or casing is integral with the remainder of the casing, is faced off internally and is provided with a liberal center opening. A portion at least of the tubular chamber is internally machined or finished in a manner to serve as a suitable guide way for a plunger hereinafter referred to. A shaft 2 embodying a pinion 3, is so machined as to bring the pitch line of said pinion well inside of the normal diameter of said shaft. On each side of said pinion said shaft is finished to gauge, and the longer end is threaded from the pinion to the outer end, at which point it is provided with a nut 4. A disc 5 peripherally machined to fit the journal bearing in casing 1 is faced on each side, is bored to fit and is riveted to or otherwise rigidly secured to the short extension of shaft 2, with its inner wall resting lat-

100
95
105

erally against pinion 3, while a similar disc, 6 is bored and threaded to fit the threaded extension of said shaft and is screwed up tightly against the opposite side of pinion 3
5 from disc 5. A short loose sleeve 7 is placed upon shaft 2 directly against disc 6, and shaft 2 along with the discs and sleeve thus assembled are inserted within, and are rotatable upon the journal bearing of the
10 transverse chamber. In making this assembly the threaded end of shaft 2, as well as a portion of sleeve 7 is caused to protrude through the circular opening in the side wall of housing 1 and extends outward from said wall.
15 A disc type ratchet wheel 8 faced on its sides and bored and threaded to fit shaft 2, is placed thereon and screwed up tightly against sleeve 7 which will now be found to serve as a spacer, and to have provided a
20 suitable space for the insertion of the blade portion of a stub ratchet lever 9. Said lever having its blade portion bored to fit pivotally on sleeve 7 and being free to swing freely between housing 1 and ratchet wheel
25 8. Ratchet wheel 8 is further secured by the application of nut 4. Lever 9 is provided with a socket extension 10 for the reception of handle 11 which is threaded at its inner end and is adapted to enter and engage with a threaded opening in the inner end wall of
30 said socket. Near the middle of lever 9 is located a double acting dog or latch 12 which is pivotally secured thereto by pin 13, said latch being free to rock in either direction,
35 thereby permitting of either end of said dog or latch being brought into engagement with ratchet wheel 8. Near the extreme outer end of latch 12 is inserted a pin 14 hereinafter referred to. The outer end of lever 9 is fitted
40 with a latch trigger 15, which is pivotally secured by pin 16. The extreme outer end of trigger 15 is fan shaped and is provided with small cogs which face inward and is also provided with a lug or ear for use in manipulating it by hand when used in connection with handle 11, Figure 5, and near said ear is inserted a pin 17. To pin 17 and to pin 14 of latch 12 is secured a coil spring 18, having sufficient tension to cause latch 12
45 to align itself with pin 17 when said trigger is thrown in either direction, said trigger being limited in its throw by a notch like chamber which contacts with a small stop pin 19 and which is inserted in lever 9 just
50 between latch 12 and trigger 15. A plunger 20 is inserted in the tubular chamber of housing 1 and is provided with a rack or toothed section which engages with pinion 3. The upper end of plunger 20 is provided
55 with a cap like abutment 21 which is adapted to engage with the axles or other convenient portions of the vehicle, and incidental to safeguarding the meshing of plunger 20 with pinion 3, when the former nears its maximum upper movement, a guide pin 22 is in-

serted in the circular wall of the transverse chamber at a point directly opposite pinion 3, and is brought into a free sliding contact with plunger 20. On the opposite side of plunger 20 from said pinion and in order to limit the upward movement of plunger 20, a short stop pin or screw 23 is inserted in and near the upper end of the tubular chamber and protrudes within a shallow longitudinal slot of limited length which has been
75 cut in said plunger.

In the modified form of ratchet lever and handle, Figs. 6, 7 and 8, lever stub 9 of itself is a substantial duplicate of lever 9 in Figure 3 when ready for use. It is also fitted with latch 12 secured by pivotal pin 13 and also carries pin 14. Instead of trigger 15 however it is fitted with trigger 15^a secured by pin 16 and carries pin 17 which however is attached to the inner end of said trigger, while the extreme outer end thereof, is also provided with a circular, toothed area, facing inward, spring 18^a is attached to pin 14 of the latch and also to pin 17 of the trigger which causes latch 12 to change
80 its alignment to correspond with the manipulation of trigger 15^a, the latter's movement being limited by its contact with stop pins 24 and 25. A telescopic handle is devised by adopting a piece of suitable tubing 26, the inner end being insertable in socket 10 and provided with a threaded portion which enters and engages the threaded opening at the inner end of said socket. Adjacent to socket 10, tube 26 is fitted with a freely sliding sleeve 27, the inner end of which is fashioned into a toothed gear. Said sleeve contains a slotted opening 28. A pin or screw 29 passes through said slotted opening and is secured to tube 26, thereby affording
85 100 said sleeve a limited lateral movement but otherwise fixing its relation to said tube.

The final diameter of the outer end of tubes 26 is slightly reduced by cutting a horizontal slot into it several inches in length, 110 after which a sleeve 30, having a slight internal taper is driven into it, thus compressing it until the slot is practically closed at the outer end. A second tube 31, a trifle shorter than tube 26 and having an external 115 diameter that fills and slidably fits the extreme contracted end of tube 26, is upset at its inner end and dressed to a full but sliding fit in the unreduced portion of tube 26, thus permitting it after insertion, to be 120 drawn partly out in tube 26 or until its enlarged portion arrests it by reason of its entering and wedging in the reduced portion of tube 26 and whereby a double length handle of a rigid, powerful and most convenient 125 form, is produced, and whereby the entire double handle may be turned to either the right or left, for the purpose of manipulating triggers 15 and 15^a without having to reach down or under protruding portions 130

of the vehicle. The outer end of tube 31 is fitted with a button or knob 32 which limits its inner position in tube 26, thereby maintaining it within easy reach when necessary 5 to withdraw and use it, as well as for providing means for withdrawing it. The open side of the transverse chamber in housing 1 is finally closed by means of a thin metal plate 33, which is secured by bolts or screw 10 34.

Referring now more specifically to the modifications presented in Figures 9, 10, 11, and 12, they deal almost exclusively with slight changes in the method of supporting 15 discs 5 and 6 in connection with shaft 2 and pinion 3. In so doing, housing 1^a has a slightly deeper transverse chamber than housing 1. The addition being confined to 20 housing 1^a disc 5 and 6 in connection with shaft 2 and pinion 3. Within said transverse chamber a rocking saddle shaped member 1^b is inserted and is pivotally supported by a pin or bolt 1^c, said saddle contacts with disks 5 and 6 for a limited space almost directly 25 underneath pinion 3 and also for a limited space directly opposite said pinions at a right angle from its center considered horizontally, and between said contact spaces or areas it is provided with a clearance chamber. The lower end of said saddle is forked 30 for a short distance in order to permit plunger 20 to intrude and move up and down between said forked portions. Pin or bolt 1^c is located slightly to the right of the 35 center of pinion 3 and discs 5 and 6 when considered vertically. On the opposite side of plunger 20 from pinion 3, a guide or bearing block 22^a takes the place of the pin 22 disclosed in Figure 1, block 22^a is secured 40 to housing 1^a by a bolt 22^c. Block 22^a extends between discs 5 and 6 from housing 1^a until it touches lightly or affords a sliding contact for plunger 20, while that portion of 45 said block which rests against the housing 1^a is provided with thin abutment like extensions, which lie directly between housing 1^a and the rims of discs 5 and 6, and provides a journal like contact or bearing for said disc over a limited area. It will now be observed 50 that when resistance is offered to the upward movement of plunger 20, the downward force extending through pinion 3 and discs 5 and 6 is finally delivered upon the lower point of saddle 1^b and entirely to one 55 side of pivotal pin 1^c and that thereby the upper point of saddle 1^b is caused to exert a portion of said force horizontally against discs 5 and 6, which in turn forces them against guide and bearing block 22^a, and 60 which by its gripping action absolutely prevents the pinion and discs from rotating backward by action of resistance or load. Furthermore by reason of the slight change 65 in the housing and the introduction of saddle 1^b and bearing block 22^a, internal ma-

ching of the housing can be dispensed with and at the same time plunger 20, and all rotative parts, as well as operating levers are interchangeable and usable with housings disclosed in Figures 1, 2 and 3 as well 70 as housings 7, 10 and 11.

In operation the device as shown in Figures 1 to 8 is exceedingly simple and effective. The pitch diameter of the pinion is slightly less than $\frac{1}{2}$ the diameter of the discs, 75 thus bringing the resistance of the load as applied to it by the plunger relatively near the center of the pinion and discs. The entire load upon the pinion is transferred directly to the discs which in turn contact entirely at their periphery upon the journal bearings afforded within the transverse chamber of the housing, and therefore at a point quite distant from the center of the pinion and whereby the frictional resistance 80 at the rim of the discs is approximately ample to prevent the pinion and discs from rotating backwards by reason of the load, thus causing the load, the plunger, the pinion and the discs to remain at rest in any 85 position in which they are left without the aid of the operating lever or any other form of latching device.

As a safeguard however, and in order to slightly increase said frictional resistance in 95 Figures 1 to 3, a clearance chamber of moderate length is provided in the journal portion of the housing directly underneath pinion 3 and whereby, a very slight wedging or impinging action is caused to take effect 100 between discs 5 and 6 and the journaled walls of the housing, thus rendering the device positively proof against danger of self reversing under load pressure or resistance, even under perfect lubrication. Assuming, 105 however, that the device is being operated with lever 9 and handle 11 which calls for hand manipulation of trigger 15, it will be observed that by pushing the outward end of said trigger downward, the lower jaw of 110 dog or latch 12 will be caused to engage with ratchet wheel 8. The lever and handle will now be free to rise without resistance, but will engage on its downward stroke, thus turning the sprocket wheel, discs and pinion 115 in a corresponding direction which in turn will force the plunger and load upward. By reversing trigger 15 and latch 12 the upper jaws of said latch will engage and the movements of the load and all rotatable parts will 120 be reversed, and in doing so the load itself will furnish at least 90% of the force necessary to establish said reverse movement. If the device be fitted with lever and telescopic handle disclosed in Figures 6 and 7 handle 125 26 is first inserted in socket 10 and screwed into the thread at the bottom of the socket part way, or say 2 or 3 revolutions, sleeve 27 is then slid forward until it meshes with the teeth on trigger 15^a. Inner tube 31 of the 130

telescopic handle is now drawn out to its limit, and the device can now not only be slid under the vehicle and be placed in proper position, but trigger 15^a can be manipulated by turning the entire handle to the right or left, and an exceptionally heavy load be raised with perfect ease, and while the operator remains in a standing or comfortable stooping position.

- 10 The chief advantages in my device are substantially as follows: Cheapness of construction in proportion to merit. Simplicity and ease of application and operation. Self locking under load without the aid of latches. Ease with which the load can be raised and let down. Effectiveness even with a lever travel of but 10 degrees. Absolute safety, coupled with the fact that the operator can stand almost erect in applying and using my device. There are a number of minor details of construction in my device which can be readily changed without departing from the spirit of invention, and I do not wish to be held strictly to such details.
- 15 It is also quite evident that other means for rotating the discs and pinion are applicable. In fact I have already a design in which the housing is widened out, and disc 5 has a bevel gear formed thereon, and 20 which is operated by a bevel pinion in the same manner as that employed in my application No. 285,075 of March 25th, 1919 for improvements in steering gears, thereby rendering the chief element of my invention admirably adapted to steering gears as well as pinion driven lifting devices.

It is also evident that while my drawing discloses an annular bearing for discs 5 and 6 still a complete or continuous circular bearing is not a necessity when used in a lifting device, since all of the pressure upon said discs is then downward, and it is then only necessary that the bearing is of such extent as to support and maintain the discs journal fashion in their proper positions.

45 What I claim is:

1. In a plunger actuating device, the combination of a housing having a longitudinal chamber and a relatively large transverse chamber therein, a journal type bearing formed in said transverse chamber, a rotatable disc peripherally journaled upon the bearing in said transverse chamber, a pinion of less than one-half the diameter 50 of said disc centrally secured to and rotating with said disc, a plunger inserted in said tubular chamber and having a toothed area which engages with said pinion and means for rotating the disc and pinion.
2. The combination of a housing having a longitudinal tubular chamber and a relatively large transverse chamber, a journal bearing formed in said transverse chamber, a disc journaled upon the bearing in said

transverse chamber, a plunger inserted in 65 said tubular chamber, having a toothed area thereon, a pinion secured to and rotatable with said disc, and engaging with the toothed area of said plunger, the diameter of said pinion in relation to the diameter of 70 said disc being reduced to a point whereby when force or resistance is applied to said plunger and pinion, it will fail to exert sufficient rotative force to the disc to force it backward by overcoming the frictional 75 resistance at the latters periphery, and means for rotating the disc and pinion.

3. The combination of a fixed annular bearing, a rotatable disc peripherally journaled against the walls of said annular bearing, a pinion of less than one-half of the diameter of said disc attached to and rotating with said disc, a plunger having a toothed area thereon which engages with said pinion, a guide for retaining the plunger and pinion 85 in mesh and means for rotating the disc and pinion.

4. The combination of a fixed annular bearing, a pair of rotatable discs peripherally journaled against the walls of said 90 annular bearing, a pinion of less than one-half of the diameter of said discs located between, attached to and rotating with said discs, a plunger inserted between said discs having a toothed area which engages with 95 said pinion, and means for rotating said discs and pinion.

5. The combination of a fixed journal bearing, a rotatable disc peripherally journaled upon said bearing, a pinion secured to and rotating with said disc, a plunger having a toothed area which engages with said pinion, a guide for said plunger, a clearance chamber between said disc and a portion of said journal bearing, and located 100 substantially in line with the thrust upon said pinion and disc when they are resisted by the plunger and whereby the backward 105 rotative tendency of the pinion and disc is minimized and means for rotating said 110 pinion and disc.

6. The combination of a fixed journal bearing, a pair of rotatable discs peripherally journaled upon said bearing, a pinion secured between and rotating with said 115 discs, a plunger having a toothed area which engages with said pinion, a guide for said plunger, a clearance chamber between said discs and a portion of said journal bearing, and located substantially in line with the thrust upon 120 said pinion and discs when they are resisted by the plunger, and whereby the backward rotative tendency of said pinion and discs is minimized and means for rotating said pinion and discs.

7. In a plunger actuating device a housing having a longitudinal chamber and also a transverse chamber therein, a plunger in-

serted in said longitudinal chamber, and having a toothed section thereon, a pinion engaging with said toothed section and actuating said plunger, a rotatable member rigidly secured to said pinion, said member having a peripheral support within said transverse chamber which is fully twice the

diameter of said pinion, and means, for rotating said member and said pinion.
